STAPLE BENDER

Carl W. Otis, Menands, N. Y.

Application January 29, 1941, Serial No. 376,554

6 Claims. (Cl. 1—50)

My invention relates to the attachment of price tickets to merchandise, and has among its objects and advantages the provision of an improved pin bender for securing pin tickets to the goods.

In the accompanying drawings:

Figure 1 is an end elevational view of the pin bender illustrating its application to a staple for securing the price ticket to an article;

Figure 2 is a view similar to Figure 1 illustrating the bent staple legs and securing the price ticket to the article;

Figure 3 is a side elevational view;

Figure 4 is a sectional view along the line 4—4 of Figure 5;

Figure 5 is a sectional view along the line 5—5 of Figure 3;

Figure 6 is a view similar to Figure 5 but illustrating a different form of pin bender;

Figure 7 is a side elevational view of the structure of Figure 6;

Figure 8 is a view similar to Figure 6 but illustrating another form of pin bender;

Figure 9 is a side elevational view of the structure of Figure 8;

Figure 10 is an elevational view of another form of pin bender; and

Figure 11 is a view taken from the position indicated by line 11—11 of Figure 10.

In the embodiment selected to illustrate my invention, I make use of a metallic finger ring 10 cut at 12 and provided with a flat extent 14. Ring 10 fits the forefinger of the hand and the flat extent 14 tends to restrain the ring from relative rotary movement on the finger. In severing the ring at 12, the ring may be made from metal which permits bending to accurately fit the ring on the finger, but the stiffness of the ring is such as to maintain its shape after fitting for normal use.

A spring steel band 16 is riveted at 18 intermediate its ends to the finger ring 10 diametrically opposite the flat extent 14. Band 16 is of such configuration as to tightly embrace the finger ring 10, and the ends of the band are provided with loops 20 for the reception of pins 22 secured to flanges 24 along the side margins of pin bending plates 26 and 28. Pins 22 are located at the lower ends of the pin bending plates 28, and the upper ends of the plates are pivotally connected together by means of a pin 30. A tension spring 32 has its ends hooked over the pins 22 and coacts with the band 16 for normally supporting the pin bending plates 26 and 28 in the normal positions of Figs. 1, 3 and 5.

The upper end of the pin bending plate 26 extends slightly beyond the same end of the plate member 28, and each plate member is provided with a pin guiding groove 34 which tapers to the vanishing point closely adjacent the lower end of its respective plate member. Both grooves are identical with the exception that the groove in the plate member 26 extends about the upper end of the plate member, as indicated at 36 in Figs. 3, 4 and 5. The grooves are arranged in a common line intermediate the side margins of the two plate members 26 and 28, and the upper end of the plate member 26 is of such curvature as to pass between the legs 38 of a staple connected with a price ticket 40 to be secured to the fabric 42. In running the groove 34 in the plate member 26 across the upper end thereof, continuity is provided for the two grooves, which grooves constitute guides for the legs 38 as the ends thereof are pressed downwardly on the plate members. In addition, the upper end of the plate member 26, in being projected beyond the same end of the plate member 28, locates the groove 34 in the plate member 26 about its curved end in such a position as to guide the leg 38 pressed therein into the groove 34 in the plate member 28 without obstruction. In other words, the leg will transfer smoothly from the terminus of the groove in the plate member 26 into the groove 34 in the plate member 28.

In operation, the finger ring 10 is preferably placed on the first finger in such manner as to project the pivotally connected ends of the plate members 26 and 28 toward the thumb of that hand. The staple of the price ticket is passed through the fabric and the staple is positioned in accordance with Fig. 1 with the legs 38 in the groove 34 in the upper end of the plate member 26. At this time the price ticket is forced downwardly on the device through thumb pressure which causes the legs 38 to bend in a spreading direction. As the legs bend, the fabric is brought into engagement with the upper end of the plate member 26 so that continued pressure on the price ticket causes the plate members 26 and 28 to be pivoted to the position of Fig. 2, at which time the legs 38 are bent to their final positions and in pressure engagement with the fabric 42 so as to effectively secure the price ticket 40.

In referring to Fig. 2, it will be noted that the plate members 26 and 28 pivot to positions which bring the axis of the pin 30 beneath a straight line passing through the axes of the pins 22. The final position of the plate members 26 and 28, as in Fig. 2, is determined by stops 44 which

project outwardly from the flat extent 14. Thus the plate members 26 and 28 may be pivoted with a snap action to the positions of Fig. 2, with the stops 44 constituting bumpers which afford protection for the finger ring 10. While the finger ring is relatively stiff, the ring is bendable by the fingers for the purpose of securing proper fitting, so that heavy impacts between the pivoted ends of the plate members and the ring are restrained from deforming the ring by reason of the stops 44.

In Fig. 1, the angular alignment of the plate members 26 and 28 is such as to facilitate passage of the two plate members between the legs 38 as pressure is exerted on the price ticket. To secure close pressure engagement between the legs 38 and the fabric 42, the plate members pivot to the position of Fig. 2 so as to impart sufficient bend to the legs for securing such engagement.

In pivoting the plate members 26 and 28 from the positions of Fig. 1 to the positions of Fig. 2, the band 16 is flexed and the tension spring 32 is elongated. Both the band and the spring exert a pull on the plate members 26 and 28 in the direction of the pin 30, and the plate member 26 is provided with an enlargement 46 which engages the coil spring 32 intermediate its ends and bends it to a position between the two stops 44. Because of the bend in the coil spring, the latter exerts pressure on the enlargement 46 and pivots the two plate members to bring the axis of the pin 30 above a straight line extended through the axes of the pins 22. As the pivoted end of the two plate members is moved a predetermined distance by the coil spring 32, the coil spring and the band 16 snap the two plate members back to the normal positions of Figs. 1 and 5. In vanishing the grooves 34 near the outer ends of the plate members 26, the angular contour of the grooves also facilitates final bending of the legs 38 and expose the outer end margins of the legs to the fabric so that these ends may be pressed firmly thereagainst.

In Figs. 6 and 7, the finger ring 46 is provided with two flanges 48 which carry pins 50 extending loosely through slots 52 in the flanges 54 along the side margins of pin bending plates 56 and 58, each of which is provided with two pin guiding grooves 60. The plates are pivotally connected together in the same manner as the plate members 26 and 28 by a pin 62. A tension spring 64 has its ends connected to lugs 66 secured to the inner faces of the plates near their lower ends. Spring 64 is located between the two flanges 48, which flanges are recessed at 68 to provide accommodation for the enlargement 70 on the plate 56 as the two plates pivot to their pin bending positions, so that the flanges 48 constitute stops. Plates 56 and 58 function in the same manner as the plate members 26 and 28, and the grooves 60 are identical with the grooves 34. Since the tension spring 64 is normally located considerably above the bottoms of the recesses 68, the enlargement 70 will, of course, flex the spring as the two plates are moved to their final positions for pin bending purposes, so that the spring 64 will act to kick the pivoted ends of the two plates and move the axis of the pin 62 above the straight line passing through the axes of the pins 50.

According to Figs. 8 and 9, the plates 72 and 74 are identical with the plates 56 and 58, with the exception that crossed bars 76 are pivotally

connected with ears 78 on the finger ring 80 by means of pins 82, and to the plates by means of pins 84 carried by lugs 86 also secured to the plates. A pin 88 pivotally connects the upper ends of the plates 72 and 74 one to the other, and each plate is provided with two grooves 90.

Fig. 8 illustrates the upper ends of the bars 76 as being provided with flat ends 124 having engagement with the inner faces of the plates 72 and 74 in their normal positions. The lower ends of the bars are also provided with faces 126 which engage the finger ring 80. These faces provide a stabilizing action for the parts concerned and restrain the tension spring 128 from urging the plates 72 and 74 beyond their normal positions of Fig. 8.

In the structure of Figs. 10 and 11, the finger ring 92 is rectangular in contour but is severed at 94. To the end wall 96 is secured two pins 98 which ride freely in a slot 100 in a bar 102 held closely to the end wall 96 by the heads 104 of the pins 98. The pin bending plates 106 and 108 are provided with pin guiding grooves 110, and the upper ends of the two plates are pivotally connected one to the other by a pin 112. Pin 112 also extends through an opening in the upper end of the bar 102, and the lower ends of the plates normally ride on the upper wall 114 of the finger ring, with the lower pin 98 lying at the bottom end of the slot 102 so as to restrain the two plates from pivotal movement in the direction of each other beyond the positions of Fig. 10.

The plates are recessed at 116 for accommodating a coil spring 118 having legs 120 lying in grooves 122 in the plates 106 and 108 for pivoting the plates in the direction of each other. When pressure is applied to the upper ends of the plates 106 and 108, the bar 102 slides downwardly of the finger ring 92, since the pins 98 fit loosely in the slot but support the bar at right angles to the longitudinal axis of the finger ring 92. The tension of the coil spring 118 is such as to snap the plates to their normal positions of Fig. 10.

Having thus described certain embodiments of my invention in detail, it is, of course, understood that I do not desire to limit the scope thereof to the exact details set forth except insofar as those details may be defined in the appended claims.

I claim:

1. A hand manipulated staple bender comprising: A finger ring; a pair of normally convergent, pivotally connected pin benders, said pin benders converging to an apex receivable between the pins of a staple pressed thereon; supporting movable means connecting the pin benders with said ring to pivot the pin benders to positions substantially in a common plane for bending the pins of the staple; resilient means acting on said pin benders to yieldingly support the latter in their normally convergent positions; and stop means on said ring arranged to engage the pin benders to limit relative pivotal movement therebetween when pivoted in pin bending directions; said pin benders being pivotal in a pin bending direction to reversed converging positions, with said resilient means acting on the apex of the reversed converging pin benders to pivot the latter beyond dead center positions and to their normally convergent positions.

2. A hand manipulated staple bender comprising: A slotted finger ring of bendable material; a pair of normally converging, pivotally connected pin benders, said pin benders converging to an

apex receivable between the pins of a staple pressed thereon to bend the pins substantially ninety degrees each when said pin benders are pivoted to positions substantially in a common plane; said pin benders being movable to reversed convergent positions in their extreme end bending positions; resilient tensioning means interconnecting said pin benders and acting on the apex of the reversely converging pin benders to pivot the latter beyond dead center positions and to their normally convergent positions; and a resilient band secured to said rings and having its ends pivotally connected with said pin benders to urge the latter to their normally convergent positions when said pin benders are moved beyond dead center positions by said resilient tensioning means.

3. A hand manipulated staple bender comprising: A finger ring; a pair of normally convergent, pivotally connected pin binders, said pin binders converging to an apex receivable between the pins of a staple pressed thereon; crossed bars pivotally connected with the pin binders and said finger ring for movably connecting the pin binders with the finger ring and to pivot the pin binders to positions substantially in a common plane for bending the pins of the staple; and resilient means acting on said pin binders to yieldingly support the latter in their normally convergent positions.

4. A hand manipulated staple bender comprising: A finger ring; a pair of normally convergent, pivotally connected pin binders, said pin binders converging to an apex receivable between the pins of a staple pressed thereon; and a slidible

guiding connection between said pin binders and said ring guiding the pin binders to positions substantially in a common plane when bent to pin bending positions.

5. A hand manipulated staple bender comprising: A finger ring; a pair of normally converging, pivotally connected pin binders, said pin binders converging to an apex receivable between the legs of a staple pressed thereon; a slotted guide member connected with said pin binders; and pins secured to said ring and slidable in the slot in said member to guide the latter in a reciprocatory path, said pin binders having camming engagement with said ring to be moved to end bending positions substantially in a common plane upon movement of said slotted guide member in one direction.

6. A hand manipulated staple comprising: A finger ring; first and second pin binders, the first pin binder having one end pivotally connected with the second pin binder slightly inwardly of one end to project the latter-mentioned end beyond said first-mentioned end; movable means connecting the first and second pin binders with said ring, said first and second pin binders normally diverging in the direction of the ring; and resilient means acting on said first and second pin binders to yieldingly hold the same in said diverging positions; said first and second pin binders each having a pin guiding groove aligning with the groove in the other pin binder, with the groove in the second pin binder extending about said second-mentioned end.

CARL W. OTIS.
